UNITED STATES PATENT OFFICE.

CORNELIUS B. CORCORAN, OF PHOENIX, ARIZONA, ASSIGNOR TO UNDERWOOD TYPE-WRITER COMPANY, OF NEW YORK, N. Y., A CORPORATION OF DELAWARE.

TIME STAMP.

Application filed June 7, 1921. Serial No. 475,635.

This invention relates to time stamps, to improved means for operating stamps of this kind, and to mechanism for counting the operations thereof. One feature of the invention is the provision of means whereby the operation of the time stamp is rendered easier for the operator. For this purpose, the time stamp plunger, the operation of which requires a large amount of force to be exerted against the action of a strong spring, is operated by an electric motor when the circuit therethrough is closed by the operator. A further advantage of the motor-operated plunger lies in the fact that the same pressure is exerted upon the plunger every time it is actuated, thus producing sharp ink impressions of the same shade. The operation of the plunger by an electric motor insures the application of a smooth regular force to the plunger at each stroke, and thus prevents misuse by a large number of operators, each striking the plunger in his individual manner.

A further feature of this invention is the mounting of a counter upon the time stamp in the path of the plunger, so that the number of times the latter is operated will be registered. This feature is useful for various purposes. For example, where the stamp is used for recording the time of receipt on order memorandum slips, such as repair calls, the counting mechanism keeps track of the total number of such calls received during the day.

It may sometimes be desired to apply the stamp temporarily to a use which is distinct from that in connection with which the total is kept. In such a case, it is desirable to disable the counter for the time being. For this purpose, the counter is movably mounted, and means are provided for moving the counter into and out of co-operative relationship with the time-stamp plunger.

Other features and advantages will hereinafter appear.

In the accompanying drawings,

Figure 1 is a front elevation, partly broken away, of a time stamp with the invention applied thereto.

Figure 2 is a plan view of the device shown in Figure 1.

Figure 3 is a side view of the counter mounted on its supporting bracket, the latter being sectioned.

Figure 4 is a front view of the counter mounted on its supporting bracket.

Figure 5 is a view showing the structure of the connecting belt.

Referring to the drawings, there is shown a time stamp 10, comprising a body-part 11, having an opening 12 in its upper surface to expose an underlying ink ribbon beneath which are located printing types carried by mechanism operated to correspond with the time as shown by a clock 13. A work-piece, which may be a card or sheet, is positioned on the upper surface of the body-part between suitable guides 14 and 15, and the ink impression indicating the time is produced on the under surface of the work-piece by rapidly lowering a plate 16, carried on the lower end of a plunger 17. To produce a clear impression, a sharp blow must be struck on the upper end (usually a knob, such as 18) of the plunger 17 against the action of a strong spring (not shown) which restores the plunger to initial position when the force is removed. The plunger is guided for vertical movement in the vertical bore of a sleeve 20, formed at the end of a bracket 21, fixed to the body-part. All of the parts enumerated above are well known in the common form of time stamp, and, therefore, need not be described in further detail. The time stamp rests upon a base 25, to which it may be held by brackets 26, and a felt pad 27 may be interposed between the base of the stamp and the base 25 to deaden the noise of operation.

As noted above, a heavy blow must be struck against the action of the strong spring to operate the plunger downwardly and cause the types to print against a card or sheet lying on the upper surface of the body-part. To minimize the amount of work necessary to be expended by a person operating the time stamp, there is fixed to the plunger 17 a cross-bar 30 having a horizontal channel therethrough, through which channel passes a belt 35. The two branches 31 and 32 of the belt are united at a point below the base 25 which, in this instance, forms the top of a stand 36, one of the branches (here shown as branch 32) continuing downward and being fastened eccentrically to the armature 40 of a motor 41 mounted in the stand 36. The motor may be like the motor shown in the pat-

ent to Anderson, No. 900,642, granted October 6, 1908. It will be seen that, upon actuation of the motor, the belt will be wound upon the armature shaft 42, thereby drawing upon cross-bar 30, plunger 17 and plate 16 to cause the types to print against a work-piece, such as a card or sheet. To close the circuit of the motor, there is provided a handle 45, fixed to a shaft 46, held in brackets 47 beneath the base 25, said shaft having an arm 48 fixed thereto. A strip of insulating material 49 is fixed to arm 48 and has attached thereto a binding post 50 which carries a contact spring 51. When the handle 45 is operated rearwardly, contact spring 51 will be brought into engagement with a contact spring 55 carried by an insulating strip 56, to which is fastened a binding post 57. When contact spring 51 engages contact spring 55, the current, which may be supplied from the usual lighting circuit, passes through the motor which is connected to the contact springs by conduits 61 and 62, and is set in motion to wind up belt 35 on shaft 42, and draw the plunger downwardly. The operator presses handle 45 rearwardly until the plunger has been drawn downwardly part way, whereupon the handle is released to break the circuit, the momentum of the motor being sufficient to complete the stroke. When the handle 45 is released by the operator, it is drawn forwardly by a spring 65 to break the circuit through the motor. The plunger is raised by its return-spring to initial position, and, in so doing, unwinds the belt from shaft 42.

For counting the number of times a time stamp is operated, there is mounted upon a horizontal arm 70 of bracket 21, a counter 71 which may be of an ordinary type, such as the well-known Veeder cyclometer. The plunger 17 has a flange 72 which, in its downward movement, engages a roller 73 on a counter-operating arm 74 fixed to the operating shaft 75 of the counter, and thereby depresses the arm 74 to operate the counter. When the plunger is restored to initial position by its spring, the arm 74 will also be restored by a spring, as is usual in counters of the type mentioned.

It may become necessary or desirable at times to disconnect the counter from the time stamp when the latter is to be used for purposes of which no account is kept. For this purpose, the mounting of the counter upon the bracket 21 is made to comprise a bracket 80 fixed to arm 70, preferably by a screw 81, bracket 80 having a horizontal portion 82 provided with a dove-tail mortise 83 into which fits a tenon 84 on the lower surface of the counter frame, said tenon being slidable laterally in said mortise to move the counter into or out of operative relationship to said flange 72 on the plunger. For moving the

counter, there is provided a rock-arm 86 65 passing through the horizontal portion 82 of the bracket 80 and lodging in a cavity in the counter frame, said rock-arm being fixed to a shaft 87, journaled in bearings 88, formed on the bracket 80, and having an operating handle 89 on its outer end. It will be seen that, when handle 89 is operated to the right, arm 86 will draw the counter to the right, thus moving roller 73 out of the path of flange 72, and, when the handle 89 is moved to the left, the counter is restored to effective position. To hold the counter in effective or ineffective position, there may be provided a spring detent 90 in bracket 80, engaging in either of two co-operating 80 grooves in the base of the counter.

Variations may be resorted to within the scope of the invention, and portions of the improvements may be used without others.

Having thus described my invention, I 85 claim:

1. The combination with a time-stamp having a plunger for pressing a work-sheet against the printing surface on said stamp, of a belt connected to said plunger, and an 90 electric motor having an armature to which said belt is attached, so that operation of the armature winds said belt upon said armature to actuate said plunger.

2. The combination with a time-stamp having a plunger for pressing a work-sheet against the printing surface on said stamp, of a belt connected to said plunger, an electric motor having an armature to which 100 said belt is attached, so that operation of the armature winds said belt upon said armature to actuate said plunger, and manually-operated means for controlling the operation of said motor.

3. The combination with a time-stamp 105 having a plunger for pressing a work-sheet against the printing surface on said stamp, of a belt connected to said plunger, an electric motor in an electric circuit, said motor having an armature to which said belt is 110 attached, said motor operating when the circuit is closed to wind said belt upon said armature to actuate said plunger, a circuit-closing device within the circuit, and manually-operated means for operating said device to close the circuit.

4. The combination with a time-stamp having a plunger for pressing a work-sheet against the printing surface on said stamp, of a belt connected to said plunger, an electric motor in an electric circuit, said motor having an armature to which said belt is 120 attached, said motor operating when the circuit is closed to wind said belt upon said armature to actuate said plunger, a circuit-closing device within the circuit, manually-operated means for operating said device to close the circuit, and means for nor- 125

mally maintaining the circuit open and for breaking the circuit when said manually-operated means is released.

5. The combination with a time-stamp having a plunger for pressing a work-sheet against the printing surface on said stamp, of a belt connected to said plunger, an electric motor in an electric circuit, said motor having an armature to which said belt is attached, said motor operating when the circuit is closed to wind said belt upon said armature to actuate said plunger, a circuit-closing device within the circuit, manually-operated means for operating said device to close the circuit, and means for normally maintaining the circuit open and for break-

ing the circuit when said manually-operated means is released, said belt unwinding from said armature when said plunger is restored to initial position.

6. In a stamping device having a printing surface, a movable member for pressing a work-sheet against the printing surface, a shaft, power mechanism for driving the shaft, manual means for controlling the operation of the power mechanism, and means connecting the power mechanism and the movable member, arranged to prevent actuation of the device more than once for each actuation of the manual controlling means.

CORNELIUS B. CORCORAN.
